GUARD FINGER AND LEDGER PLATE

Original Filed June 5, 1925

UNITED STATES PATENT OFFICE

CHARLES F. HOVER, OF CONRAD, MONTANA

GUARD FINGER AND LEDGER PLATE

Application filed June 5, 1925, Serial No. 35,194. Renewed August 27, 1929.

This invention relates to new and useful improvements in guard fingers and ledger plates for mowing machines.

One object of the invention is to provide a ledger plate which is held in the guard finger without the use of bolts or rivets, and which is constructed to permit the easy application and removal without the use of special tools.

10 Another object is to provide a guard finger and ledger plate therefor, which is so constructed that a single movement of a nail, or like instrument, unseats the plate, and a single movement restores the plate to its seat.

15 A further object is to provide a ledger plate which is adapted to expand the seating spring so that said spring will frictionally remain in position to prevent any loose motion of the plate.

20 Other objects and advantages will be apparent from the following description when taken in connection with the accompanying drawing.

In the drawing:

25 Figure 1 is a top plan view of a guard finger showing the ledger plate in position.

Figure 2 is a vertical longitudinal central sectional view, on the line 2—2 of Figure 1, showing the use of a large nail for unseating the plate.

30 Figure 3 is a similar sectional view showing the use of the nail when restoring the plate to its seat.

Figure 4 is a vertical transverse sectional view on the line 4—4 of Figure 1, showing the bevel faces of the guard finger and ledger plate.

35 Figure 5 is a horizontal sectional view on the line 5—5 of Figure 2, showing the spring and tapered nose of the ledger plate.

Referring particularly to the accompanying drawing, 10 represents the body of the guard finger which has the longitudinal cavity 11, provided with the rear end wall 12, and in the forward end of the finger there is formed a socket 13, in which is seated the coil spring 14. The upper face of the said rear wall 12 is formed with a recess 15, the side walls 16, of which converge rearwardly, and are underbeveled.

Properly disposed on the guard finger, in covering relation to the cavity, is the ledger plate 17. The side portions of the ledger plate are underbeveled forwardly of the wall 12, to provide the usual cutting edges, and at 55 the rear or wider end of the plate the corners are cut off obliquely, as at 18, and such oblique portions are beveled on their upper sides to snugly fit beneath the underbeveled walls 16, of the recess 15. Formed centrally on the forward or narrower end of the plate 17, is a forwardly extending and tapered nose 19, which is arranged to enter the adjacent end of the coil spring 14, the inclined sides of said nose causing the convolutions of the spring to 60 expand and snugly and frictionally engage the walls of the socket 13, with the result that the forward end of the ledger plate is firmly held against any tendency to move sidewise. The normal expansive force of the spring 14 70 urges the ledger plate rearwardly so that its beveled portions 18 firmly engage with the underbeveled walls of the recess 15.

Formed centrally in the rear or wider end of the ledger plate is an elongated open-ended slot 20, the forward or closed end of which overlies the rear portion of the cavity 11, in advance of the rear wall 12 of the cavity, to permit the introduction of the end of a nail 21, as shown in the drawing, as will be 75 later described. The forward portion of the slot 20 is disposed so that the wall thereof cooperates with the adjacent portion of the wall 12, whereby when the pointed end of a nail is inserted in said slot and rocked rearwardly, the said pointed end of the nail will press the rear end of the ledger plate upwardly so that the beveled faces 18 will slide 80 upwardly and forwardly against the beveled walls 16, and the plate moved forwardly 90 against the tension of the spring 14, to completely unseat the plate.

To replace the ledger plate, the operator places the plate over the cavity of the guard finger so that its nose 19 is disposed within 95 the adjacent end of the spring 14, and then inserts the pointed end of the nail in the slot 20 and rocks the nail forwardly so that the pointed end thereof bears against the forward face of the wall 12, while the portion 100

of the nail, adjacent the point bears on the forward end wall of the slot. This operation serves to press the ledger plate downwardly and forwardly, against the tension of the spring 14, and forwardly of the recess 15, with the result that the spring 14 will act to snap the rear end of the plate beneath the underbeveled walls 16.

It will be noted that a single movement of the nail is required to unseat the plate, and that a single movement is required to seat the plate, thus rendering the replacement of ledger plates a simple and easy operation, and one requiring a very short time.

There is thus provided a guard finger unit, including a guard element and a ledger plate, both of which are so constructed as to co-operate to hold the ledger plate against any movement with respect to the guard element, and also wherein the ledger plate can be easily and quickly seated in the guard element or removed therefrom.

What is claimed is:

A guard finger having a ledger plate seat having rearwardly converging underbeveled side walls, a ledger plate on the seat having its rear end formed with rearwardly converging and beveled side walls engaged beneath the side walls of the seat, said rear end of the ledger plate having a notch the innermost portion of which normally lies forwardly of the seat to permit introduction of a ledger plate prying tool, and resilient means carried by the guard finger and engaging with the other end of the ledger plate for urging the latter into the seat and for projecting the ledger plate rearwardly out of the guard finger upon lifting action by such tool.

In testimony whereof, I affix my signature.
CHARLES F. HOVER.
